ART OF COMBUSTION OF LIQUID FUELS

Eben H. Carruthers, Ithaca, N. Y., assignor to
 United Furnace Engineering Company, Inc.,
 New York, N. Y., a corporation of Delaware

Application May 19, 1931, Serial No. 538,453

10 Claims. (Cl. 158—117.5)

This invention relates to the art of combustion of liquid fuels, particularly oil, especially for use in the burners of furnaces in which close control of the combustion and resulting gases is 5 desirable.

In all prior liquid fuel combustion systems of which I am aware, the regulation of the flow of liquid fuel is by the employment of a valve which is designed to control the pressure back of the 10 burner orifice, or by an automatic pressure reducing valve to maintain a constant pressure back of the orifice, or combinations of both. Under the old systems, it has been practically impossible to maintain the flow rate of the oil 15 constant with fixed settings of the pressure regulators and valves.

For example, changes in temperature of the oil, in the viscosity of the oil, or the building up of 20 said material in the valve or orifice, may cause wide variations in flow. These variations must be counteracted by constant manipulation of the valve or regulator, if conditions are to be kept at all constant. The result of the fluctuations 25 is a flame of uneven character, and the gases of combustion may become very detrimental to the articles in the furnace to which the heat is applied.

In melting metals or in heat treatment of 30 metals, it is very desirable to maintain a certain selected furnace atmosphere or composition of gases of combustion, to avoid certain detrimental effects on the materials subjected to heat. For example, in melting copper, a highly oxidizing atmosphere will cause oxidization of the copper; 35 on the other hand, a highly reducing flame will allow the copper to absorb carbon monoxide, which is known to be detrimental to the metal. In the case of heat treatment or annealing of ferrous metal, an oxidizing flame is injurious to 40 the surface of the metal, causing scaling; and therefore control of this atmosphere is desirable again.

A neutral atmosphere which is the dividing 45 line or small range between the oxidizing and the reducing atmosphere is usually the most desirable to maintain, but in apparatus now in use the setting of the valves or other parts is done by purely human observation of the operator, which cannot be relied on at all times.

50 Since it is desirable to maintain some particular atmosphere, it is necessary to have a constant flow rate of liquid fuel to the burner, in order to avoid the fluctuations in the ratio of the fuel to air mixture, which in turn causes fluctuations in the resulting furnace atmosphere, and

it is necessary to maintain a constant liquid fuel flow rate along with the flow rate of air that is set.

An object of the present invention is to provide 5 a new and improved method of and apparatus for producing a constant selected or predetermined furnace atmosphere or composition of gases of combustion within a furnace.

Other objects are, to provide means for effecting a constant flow rate of liquid fuel and 10 mixing said fuel with the desired proportions of air to maintain combustion, said liquid fuel being preferably atomized prior to its mixture with the air, whereby air may be supplied at low pressures; to provide a system of burning liquid 15 fuel which allows the selection of a certain furnace atmosphere, and which includes means for indicating the said furnace atmosphere and 20 means for maintaining the selected atmosphere without variations; and a method and apparatus for high combustion efficiency, applicable for 25 utilizing fuel oils of high, low and intermediate gravities.

In the accompanying drawings, which illustrate 30 various types of apparatus embodying my invention and capable of use in the practice of my method:

Figs. 1, 2 and 3 are diagrammatic views of 35 several forms of apparatus embodying my invention.

Referring first to the form of Fig. 1, 5 designates preferably a volumetric flow displacement pump designed to be driven by a suitable prime mover or motor 6 at a constant speed. This pump is coupled to a liquid fuel storage tank 7 by a suitable pipe connection 8, and is designed to deliver the liquid fuel, preferably oil, to a burner designated generally by the numeral 9. 10 designates a connecting pipe line for the 40 passage of the liquid fuel from the pump to the burner.

The burner 9 has a discharge orifice 11; the 45 area of this orifice should be of a size so that, for a set delivery rate, the pressure behind it will be high, running, for example, from 1000 pounds to 10,000 pounds per square inch.

The pressures now known to the art for spraying liquid fuels cannot be accurately called high pressures since they are but a small fraction 50 of the high pressures employed according to the present invention. At the novel pressures of 1000 to 10,000 pounds per square inch, the strain energy is supplied in such quantities that when the pressure is released, this energy is absorbed 55 as surface tension in the particles which at the

pressures mentioned are necessarily of such proportions as to present the requisite surface for the absorption, which energy is sufficient to cause vaporization or volatilization of the oil 5 when the pressure is released, it thus being impossible for the oil particles to remain as droplets and condense or coalesce of themselves as in existing methods since the entire quantity of liberated oil heretofore was not completely blown 10 into a gas but the division of the oil under the action of pressure was final at a stage where the major portion of the oil consisted of droplets of considerable size; hence by means of my invention, in combination with a flame, upon liberation 15 of the oil, I effect complete atomization, vaporization and combustion directly at the orifice. This action occurs immediately, simultaneously and instantaneously, all of the oil being blown directly and completely into a vaporous or 20 volatile state solely through pressure. Accordingly the specific pressures are not limitary but include all equivalent lower and higher pressures which produce the same results within the spirit and scope of the invention.

25 It is an important and characteristic feature of my invention that the liquid fuel is passed to the burner at a constant flow rate, and this I accomplish without the employment of valves or regulating means interposed between the 30 pump and the burner, as has heretofore been necessary.

In practice, the pump should displace, in a unit of time, a definite amount of liquid fuel regardless of the pressure it must discharge this 35 fuel against, so that the volume of liquid delivered to the burner through the connecting line 18 will be at a constant rate, regardless of the pressure in said line or back of the discharge orifice 11.

40 Due to the presence of relatively high pressure back of the discharge orifice, it will be apparent that the liquid fuel passing from the pump to the burner will be broken up into fine particles and, as it is discharged through the orifice, the drop in pressure from the high 45 values to the low pressure values will cause intense atomization of the liquid fuel, rendering it suitable for complete combustion when mixed with air.

50 As illustrated in each of the forms of apparatus shown, air is delivered to a furnace mixing chamber 12 of a furnace 13 from a fan or blower 20, and from thence the mixture of air and atomized liquid is passed to the combustion chamber 14 of the furnace through an opening 15. Since the liquid fuel has been highly atomized upon leaving the orifice 11, the air is not relied on to take any part in breaking up the liquid fuel; it is needed only to mix with the 55 atomized liquid to support combustion. Consequently, the air employed may be low pressure air supplied from low pressure fans, etc., at a considerable saving over present methods. The employment of low pressure air also has the effect of decreasing noise in the operation of the 60 burner.

The rate at which the air is supplied to the combustion chamber, when apparatus of the form of Fig. 1 is employed, may be controlled 70 by a valve or damper 16 disposed in the air line 17 connecting the blower 20 and the chamber 12. In addition to this valve 16, and at some convenient location in line 17, I provide a Venturi meter 18, or a thin plate orifice or its equivalent, communicating with a manometer or other 75

suitable indicator device 19. The function of this indicator device is to show relatively the weight-time rate of air passing through the line to the combustion space of the furnace, by indicating the pressure drop through the meter. 5

The indicator device may be calibrated in terms of percentage of gas composition of the furnace gases, thereby having the advantage of giving the operator a definite scale by which he can regulate the atmosphere to suit the requirements of the material being heated. 10

The furnace atmosphere, or the composition and relative proportions of the gases resulting from this combustion, depend upon the relative proportions or rates at which the fuel and air 15 are being delivered. Since the fuel rate is definitely fixed at a certain value, changes in the resulting gases will be effected by changes in the air rate only, which changes will be indicated on the air flow indicator 19. For every 20 position of this indicator, then, there will be a corresponding analysis of the gases resulting from combustion. These may be determined by taking samples directly from the furnace and analyzing them by any of the generally known 25 methods, and the resulting figures placed on the indicator.

After analyses are made for a sufficient number of points to form the scales of the indicator, the sampling and analysis apparatus may be 30 discarded. From then on, the readings of the scales will indicate the composition of the gases, and the operator, by adjustment of the air valve or gate, may bring the indicator to any particular scale reading and thus establish the corresponding furnace atmosphere. 35

In the operation of the form of Fig. 2, it is contemplated that the air flow is kept constant by a suitable automatic air flow regulator 21 and the pump 5 for the liquid fuel, regulated so 40 that the rate of flow of fluid may be varied to any selected rate, but after the selection the rate of flow of the liquid will be constant. In this manner, the ratio of fuel to air may be selected and controlled so as to give the desired result- 45 ing furnace atmosphere as described in connection with the form of Fig. 1. In this form of apparatus, I employ, in place of the Venturi meter 18, the regulator 21 of well known construction. This regulator may be set to allow 50 the air to pass to the furnace at a constant rate regardless of changes in the pressure of the source of supply.

A manually operable volumetric adjusting means 22 may be employed for controlling the 55 delivery of the pump, and an indicator 23 associated with the pump for indicating the percentages of the gases of combustion. The scale of the indicator may be calibrated as before, to show percentages of gases of combustion as a 60 function of the volume of liquid fuel delivered by the pump. Or the speed of the pump may be varied by the employment of a variable speed motor; and the percentages of gases calibrated in terms of said speed. 65

The operation of the form of Fig. 2 is substantially the same as described for the form of Fig. 1, with the exception that the changes in the composition and relative proportions of the products of combustion is effected by manipulation of the mechanical volumetric adjusting means of the pump, or alternatively, by regulation of the speed of the pump, and the scales of gas composition are related to the dial 23 or its equivalent, in the case of the mechani- 70 75

cal adjustment of the pump's displacement, or to the indicator of the pump's speed of rotation in the case of the speed adjustment.

Fig. 3 illustrates apparatus comprising a combination of the forms of Figs. 1 and 2. In this case, the positive blower or fan 20 and the constant volume displacement pump 5 are driven by the same power means 6, through connecting shafts or suitable gearing. The pump 5 is provided, as in Fig. 2, with the adjustable volumetric control means 22 and the dial or indicator 23, indicating the percentages of the gases of combustion as a function of the flow rate of liquid fuel therethrough. While the power means 6 is rotating at any desired constant speed, the operation and control will be identical with that of the form of Fig. 2, the rate of supply of air being constant, due to the constant speed of the blower 20.

Since the rate at which the blower delivers air and the flow rate of the pump 5 are proportional to the speed at which said units are driven, the speed of each may be changed equally without altering the relative proportions of air and liquid fuel. Hence, it is possible to vary the furnace temperature or the rate of heat liberation therein by adjusting the speed of the power means 6 without changing the selected furnace atmosphere.

To this end, a rheostat 25 or other power control device may be applied to the power means for varying the speed thereof and thereby vary the furnace temperature. This arrangement is highly desirable in providing an accurate heat control for the furnace to which the system is applied, and permits the furnace to be "banked" or maintained at a minimum temperature when not in actual use.

In prior liquid fuel combustion systems, the supplies of liquid fuel and air must be entirely shut off when the furnace is not in actual use. Due to this fact, the furnaces, ovens, etc. cool off between heats and result in considerable waste of fuel in bringing the apparatus to working temperature for the next heat.

I claim:

1. The herein described method of effecting combustion of a liquid fuel which consists in producing a flow of the liquid at a constant flow rate while subjected to high pressure at or above substantially 1000 pounds per square inch, atomizing said liquid by said pressure prior to its mixture with air, and then mixing air and the atomized liquid in predetermined proportions and igniting the mixture.

2. The method according to claim 1 in which the air mixed within the atomized liquid is at a pressure relatively low with respect to the said pressure.

3. The herein described method of effecting the combustion of a liquid fuel in a furnace, which consists in producing a flow of the liquid at a constant flow rate while subjected to high pressure at or above substantially 1000 pounds per square inch, atomizing said liquid by said pressure, then mixing air and the atomized liquid in the furnace and igniting the mixture.

4. The herein described method of effecting

combustion of liquid fuel in a furnace, which consists in producing a flow of the liquid by pressure above substantially 1000 pounds per square inch at a constant flow rate, atomizing said liquid prior to its admixture with air, and then mixing air in controlled and measured quantities with the atomized liquid and igniting the mixture.

5. The herein described method of effecting combustion of liquid fuel in a furnace which consists in producing a flow of the liquid at a constant flow rate, atomizing said liquid by pressure above or at substantially 1000 pounds per square inch prior to its admixture with air, then mixing air in controlled quantities with the atomized liquid and igniting the mixture.

6. The herein described method of effecting combustion of a liquid fuel which consists in producing a flow of the liquid while subjected to high pressure at or above substantially 1000 pounds per square inch, atomizing said liquid by said pressure prior to its admixture with air, mixing air and the atomized liquid, and igniting the said mixture.

7. The herein described method of effecting combustion of a liquid fuel which consists in producing a flow of the liquid while subjected to high pressure at or above substantially 1000 pounds per square inch, atomizing said liquid by said pressure prior to its admixture with air, mixing low pressure air and the atomized liquid, and igniting the said mixture.

8. The herein described method of effecting combustion of a liquid fuel which consists in producing a flow of the liquid while subjected to high pressure at or above substantially 1000 pounds per square inch, atomizing said liquid by said pressure prior to its admixture with air, mixing low pressure air and the atomized liquid in predetermined proportions, and igniting the said mixture.

9. The herein described method of effecting combustion of a liquid fuel in a furnace to produce a selected constant furnace atmosphere within the furnace, which consists in supplying a mixture of air and liquid fuel to the furnace in constant quantities, the liquid fuel being atomized at a pressure at or above substantially 1000 pounds per square inch, varying the quantity of one of the fluids of the mixture while maintaining the other constant, and igniting the mixture.

10. The herein described method of effecting combustion of liquid fuel in a furnace, which consists in producing a flow of the liquid at a constant flow rate while subjected to a pressure at or above substantially one thousand pounds per square inch to atomize the liquid, then mixing air in controlled and measured quantities with the atomized liquid, and in simultaneously effecting equal changes in both air and liquid flow for the purpose of changing the rate of heat liberation in the furnace without changing the atmospheric condition, and then igniting the mixture.

EBEN H. CARRUTHERS.
